UNITED STATES PATENT OFFICE

JOHN A. WIENER, OF ROTHSCHILD, WISCONSIN

REGULATING MECHANISM FOR STEAM-GENERATING PLANTS

Application filed July 15, 1922. Serial No. 575,361.

In most plants making use of steam generators, the demand for steam varies widely and often irregularly. The attempts of the boiler room attendant to regulate the supply of fuel and air and feed water in accordance with the demand for steam are little better than guess work because ordinarily they have no indication of the demand being made upon the boiler except by changes in the steam pressure gauge. There are some devices which will give an indication of the rate of flow of steam from the boiler and so assist in governing the management of the fire. These devices, however, call for intelligent interpretation of their indications and are not of much use to the ordinary boiler attendant for this reason.

It is an object of the present invention to make use of an indicating device of the class just mentioned for automatic control of the supply of fuel, air and feed water so that proper condition of the fire at all times may be easily maintained.

It is a further object of this invention to provide an automatic system by which the fire in the generating plant may at all times be kept in a condition corresponding to the demand for steam.

It is a further object of this invention to provide a number of electric motors for moving regulating devices for controlling the steam generating plant and to control said motors by an indicating device which is responsive to the demands made upon the boiler.

It is a further object of this invention to utilize the moving parts of an indicating device to control the movement of motors which shall adjust the conditions at the boiler in accordance with the conditions indicated by the indicating device.

Other and further important objects of this invention will be apparent from the disclosures in the accompanying drawings and the following specification.

The invention (in a preferred form) is illustrated in the drawings and hereinafter more fully described.

On the drawings:

Figure 1 is a diagrammatic view of a boiler

showing the application of the regulating motors thereto.

Figure 2 is a diagram of the electrical connections.

Figure 3 is a view of the driving and contacting mechanism. Figure 4 is a perspective view of the contacting mechanism.

As shown on the drawings:

There is indicated at 1 a device for interpreting the condition of the steam in terms of electrical resistances. As the details of this device are not in themselves any part of my invention, the description thereof will be limited to what is necessary in order to make the invention of this application readily understood. The instrument 1 is of an elbow shape and has connections 2 and 3 leading to the ends of an oblique tube 4. A thread of mercury extends along this tube, standing at a height therein corresponding to the difference in pressure between the two ends thereof. As steam flows through the elbow 1 a difference in pressure is created between connections 2 and 3 and the end of the thread of mercury in the tube 4 moves correspondingly. An electrical resistance 5 is connected at various points to the interior of the tube 4 so that the position of the mercury by shunting a larger or smaller portion of this resistance translates the difference in steam pressure into an electrical resistance. The position of the mercury in the tube 4, and so the resistance 5, corresponds therefore to the quantity of steam being used.

The elbow 1 also has a connection to a manometer 6 in which, in a similar way, the pressure of the steam is made to show as an electrical resistance. The elbow 1 also contains a plug inserted at 7 by means of which any form of resistance thermometer may be used to indicate the temperature of the steam in terms of an electrical resistance. The difference in pressure between the connections 2 and 3 is a direct function of the velocity of the steam through the elbow 1. The resistance at the manometer 6 corresponds to its pressure, and the resistance at the thermometer 7 corresponds to its temperature. Thus all of the factors showing the amount of

steam used and its condition have been translated into electrical resistances.

These resistances are introduced into a pair of arms of a Wheatstone bridge. The junction of the two arms containing these variable resistances is at 8. The junction of the two other arms, which contain constant resistances, is at 9. A galvanometer 70 is connected between the points 11 and 12, which are the junctions of the two pairs of arms. The first mentioned arm is from the point 8 through the resistance 5 and the wire 10 to the point 11; the second arm is from the point 8 through the manometer resistance 6, the thermometer resistance 7 and the wire 13 to one end of a rheostat 14. The resistance of this rheostat is varied by moving an arm 15, which is the pointer of the indicating device, so causing a traveling contact 16 to move along the rheostat and an arcuate conductor 17, which is connected to the point 12 by a wire 19 leading from the end 18. When the resistance of the rheostat 14, added to the resistances 6 and 7, bears to the resistance 5 the same ratio that the resistances joining at 9 bear to one another, there will be no current through the galvanometer.

Current for the Wheatstone bridge is supplied from the generator 20, one main lead comprising the wire 21 to the point 9, and the other the wire 22 to the point 8. In order that this generator may produce a constant voltage, it is preferably driven by a motor 57 of the constant speed type. The same constant speed motor operates through a train of reduction gearing 58 a cam 59 which at regular intervals causes the contact device 25 to be lifted. This contact device has a pair of upstanding projections 26, one on each side of the pivot by which the device is connected to the lifting means. The rotating part of the galvanometer carries an arm 27 which presents two obstacles 28 of slightly greater spacing than the projections 26. If no current is flowing through the galvanometer, the arm 27 will be in its central position and both of the projections 26 will hit obstacles 28 so that the device 25 is not tilted about its pivot. If, however, current is flowing through the galvanometer so that the arm 27 is not in the central position, one of these projections 26 will escape its obstacle, while the other will contact with its obstacle, with the result that the upward motion of the switch 25 will cause it to tilt about the pivot.

The tilting action of the switch 25 will cause it to engage a central contact 30 and one of the outside contacts 31 or 32. The two sides of the switch member 25 are insulated from one another, and the connections are such that these two sides, with the three contacts 30, 31 and 32, constitute a pole changer. When the pole changer is tilted to the left, so that the contacts 30 and 31 are engaged by the arm, current will flow from the power line

23 through the wire 33—34 to the contact 31, over the left hand member of the switch to the wire 35, thence through the field 36 of the motor of the indicating device to the wire 37 and along the wire 38 to the right hand member of the switch 25 and so to the contact 30, from there along the wire 39 to the armature 40 of the motor of the indicating device, and from there by the wire 41 to the other power line 24. If the current through the galvanometer is in the other direction so that the arm 27 moves in the other direction so that the switch 25 tilts to the right and engages the contacts 30 and 32, current will flow from the power line 23 over the wires 33 and 42 to the contact 32, hence up the right hand one of the members of the switch 25, through the wire 38, wire 37, field 36, wire 35, the left hand one of the members of the switch 25, the contact 30, the wire 39, armature 40, wire 41 to the other power line 34.

It will thus be seen that the current through the field 36 is in one direction or the other according to the direction of the current through the galvanometer, and that when no current flows through the galvanometer, no current will be supplied to the motor of the indicator. The arm 15 therefore rotates in one direction or the other if at the moment the member 25 is lifted there is current flowing through the galvanometer. The arm 15 makes contact both with the rheostat 14 and with the arcuate conductor 17, so that as it is moved in one direction or the other it increases or diminishes the resistance in that arm of the Wheatstone bridge containing the manometer 6, thermometer 7 and rheostat 14. It will thus be seen that the action of the indicating device is to automatically adjust the rheostat 14 to a resistance that gives no current in the galvanometer, and that this resistance is a function of the pressure, temperature and velocity of the steam going through the elbow.

To the foregoing electrical connections I have added a system of motors shown at 50, 51 and 52. One element of each of these motors, preferably the field is supplied from the main line 23—24, over wires 53 and 54. One terminal of the other element of each motor is connected to the wire 55, which joins the wire 35. The other terminal of each of these elements is connected to the wire 56, which joins the wire 38. Preferably the element thus connected to the pole changer 25 is the armature, but it may be either element as the designer desires, or if desired the motors 50, 51 and 52 may be series motors so that both elements are connected through the pole changer 25, as is the motor 120 of the indicating device.

When the pole changer 25 moves toward the left, current flows from the line 23 over the wire 33—34, contact 31, left hand part of the pole changer 25, wires 35 and 55, to the

armatures of the several motors, from whence it goes through the wire 56 and returns to the wire 38, right hand part of the switch 25, contact 30, wire 39, armature 40, wire 41 and line 24. This current is comparatively small because it must go through the rather delicate contacts of the pole changer, and also because it passes through the armature of the rather delicate motor for the indicating device. The 10 motors 50, 51 and 52, however, do not need to be small on this account, but may be of any needed power, because the other element of these motors is connected to the wires 53 and 54 directly to the power line. When the pole 15 changer 25 is in the right hand position, current flows from the line 23 through the wire 33, contact 32, right hand part of the pole changer 25, wires 38 and 56, to the several 20 motors in parallel, from whence it continues over the wire 55 to the wire 35, left hand part of the pole changer 25, contact 30, wire 39, armature 40, wire 41, to the other line 24.

It will thus be seen that the pole changer 25 reverses the current in one of the elements 25 of each of the motors 50, 51 and 52, but the current in the other elements of these motors is in a constant direction. These motors therefore rotate in one direction or the other, according to the position of the pole changer 30 25, that is according to the direction of the current in the galvanometer, and that is according to the conditions in the elbow 1. The motors, therefore, are moved in accordance with the velocity, the pressure and the temperature 35 of the steam supplied by the boiler.

The motor 50, as seen near the upper part of Figure 1, controls a valve 50' for regulating the supply of feed water to the boiler. The motor 51, as seen at the right of Figure 40 1, controls a valve 51' which regulates the supply of steam or other power to the engine 53, which drives the endless grate or other form of mechanical stoker shown at 54. The motor 52 is shown in dotted lines in the bottom of Figure 1. It controls the damper 55, by which the admission of air to the furnace is regulated. Thus the indicating device, which is sensitive to the quantity and condition of steam delivered by the boiler, is 45 made to automatically control the supply of feed water to the boiler, the supply of coal to the furnace and the supply of air to the furnace.

Under ordinary conditions, only one other 55 regulation is needed in the management of a boiler. This is indicated by the damper 56, which regulates the exit of flue gases from the furnace. I have discovered that the conditions governing the difference in air pressure 60 between the entrance point 55 of the furnace and the chimney depend on many other conditions besides the velocity, pressure and temperature of the steam delivered by the boiler. For this reason I have not provided 65 a motor governed by the indicating device

and pole changer 25 to operate the damper 56. This damper may be operated manually or may be provided with any desired automatic means, one, for example, responsive to the temperature within the fire box may be used 70 to control this motor.

I am aware that many changes may be made and numerous details of construction may be varied through a wide range without departing from the principles of this invention, and I therefore do not purpose limiting 75 the patent granted hereon otherwise than necessitated by the prior art.

I claim as my invention:

1. In combination, a boiler, means for controlling the supply of fuel, air and feed water to said boiler, motors for operating said controlling means, and an indicating and controlling device for governing the operation of said motors, said device being responsive 80 to the quantity and condition of steam supplied by said boiler.

2. In combination, a boiler, means for controlling the supply of fuel, air, and feed water to the boiler, motors for operating said controlling means, electric circuit means responsive to the quantity and condition of the steam supplied by the boiler, a pole changer in operative association with the electric circuit means to govern the operation of the 90 motors, and an indicator in circuit association with the pole changer and governed 95 thereby.

3. In combination, a boiler, means for controlling the supply of fuel, air and feed water to said boiler, motors for operating said controlling means, a Wheatstone bridge circuit responsive to the quantity and condition of the steam supplied to the boiler, a galvanometer responsive to unbalancing of the Wheatstone bridge circuit, a pole changer in operative association with the galvanometer to control the said motors, a rheostat forming the balancing resistance of the Wheatstone bridge circuit, and means whereby the pole 100 changer controls the rheostat to balance the bridge circuit.

In testimony whereof I have hereunto subscribed my name.
